(21) Appl. No.: **29/382,308**

(57) **CLAIM**

The ornamental design for a golf ball marker retention and green repair tool device, as shown and described.

(22) Filed: **Dec. 30, 2010**

DESCRIPTION

(51) **LOC (9) Cl.** 21-02

FIG. 1 is a front elevational view of a golf ball marker retention and green repair tool device showing my new design.

(52) **U.S. Cl.** **D21/793**

FIG. 2 is a right-side elevational view thereof.

(58) **Field of Classification Search** D21/789,

FIG. 3 is a rear elevational view thereof.

D21/793, 794; 473/285, 286, 406, 408

FIG. 4 is a left-side elevational view thereof.

See application file for complete search history.

FIG. 5 is a top plan view thereof.

(56) **References Cited**

FIG. 6 is a bottom plan view thereof; and,

FIG. 7 is a perspective view thereof.

Any broken lines which may be shown in the views are for illustrative purposes only, and form no part of the claimed invention.
